FURNACE AND THE OPERATION THEREOF

Arthur J. Boynton, Chicago, Ill., assignor to H. A. Brassert & Company, Chicago, Ill., a corporation of Illinois

Application August 1, 1936, Serial No. 93,804

13 Claims. (Cl. 263—15)

The present invention relates to improvements in furnaces and the operation thereof.

More particularly the present invention relates to industrial furnaces operating on gaseous fuels containing hydrocarbons. Among such fuels may be mentioned coke oven gas, natural gas, and mixtures of either of these gases with blast furnace gas. The invention is equally applicable to furnaces using other gases containing hydrocarbons.

It has long been recognized that heat transfer from the products of combustion in a furnace or the like is greatly promoted by luminosity of the flame. Luminosity results in absorption of heat as a result of radiation. In the absence of luminosity, heat is transferred by conduction, and to accomplish a predetermined result a temperature is required within the furnace much higher than where luminosity exists. The result of lack of luminosity is decreased efficiency in furnace operation.

Luminosity of a flame is understood to result from the presence within the fuel stream of minute particles of solid carbon. These particles become heated to incandescence and give to the flame its luminous appearance, at the same time radiating heat.

Fuel containing hydrocarbons may be made to burn with a luminous flame by the decomposition of some or all of the contained hydrocarbons prior to combustion. Such decomposition, often called cracking, results in the formation within the gas of solid carbon particles capable of radiation and of producing a luminous flame. The present invention relates to novel means for producing cracking in the operation of an industrial furnace and the luminosity attendant thereto.

The present invention will be described in connection with furnaces such as are employed in the manufacture of steel. Such furnaces employ various gases, among which may be gas resulting from liquid fuels such as tar and oil for the creation of the necessary heating and melting effect. It is common practice to preheat such gases in regenerators. Another example of the type of gas which is used is a mixture of coke oven gas and blast furnace gas. Such gases are commonly available at steel works and are frequently wasted except in connection with the manufacture of steel. The purpose of regeneration of the fuel gas is, in part, to recover the heat from the outgoing waste gases by raising the temperature of the ingoing fuel. A second and very important object is, however, to crack the hydrocarbons, chiefly methane, in the gaseous mixture, and

thereby impart luminosity to the flame. According to prior constructions and prior methods, regeneration under these conditions involves certain expensive and undesirable constructional features and imposes limitations on the operation. For example, the port through which gas passes to an industrial furnace is ordinarily small in cross sectional area in comparison with the air port. At the outgoing end of the furnace, therefore, the exit gases tend to pass through the air port to the air regenerator and to heat up this regenerator to a higher temperature than desired, while the heating of the gas regenerator is less than is required for the desired cracking operation. In connection with the gases ordinarily used, the cracking of hydrocarbon gases requires a temperature in excess of 2000 deg. F., and such a temperature is not usually obtainable from the amount of gas issuing through the relatively small gas ports. It has been suggested, where the practice of regenerating the gas to cracking temperature is followed, to provide the furnace with removable gas ports to permit the necessary increased flow of outgoing gases into the gas regenerator. In addition to the inconvenience and expense of a removable port and the necessity of maintaining a minimum temperature in the gas regenerator, there are incidental disadvantages connected with the practice of heating a mixture of coke oven gas and blast furnace gas in a regenerator. Among these disadvantages is the loss of gas by reversal, since a regenerator flow of gas goes to the chimney at each reversal. The loss just mentioned may be partly overcome by shutting off the more valuable coke oven gas before reversal, but this necessity is an undesirable feature.

Among objectionable characteristic of this practice is a certain danger of explosion during reversal which attends the use of a gas mixture of high calorific power. Furthermore, it is necessary to maintain a velocity above a certain minimum within the gas regenerator, if cracking is taking place therein, in order that the particles of solid carbon may be swept along with the gas stream and not deposited in the checkerwork of the regenerator. According to the prior suggestions referred to, the regenerator must be designed for the double purpose of heating and of carrying over into the furnace all of the solid particles of carbon. In short, the objection to the prior suggestions in connection with the cracking of the gas by regeneration are of such consequence that they have resulted in the abandonment of gas regeneration in certain localities,

the operators preferring to use cold gas, for the reason that the added simplicity, together with the reduction of cost of repairs and reduction of the loss of gas, more than offsets the nominal thermal benefit of regeneration.

Where coke oven gas unmixed with blast furnace gas is used in furnaces of the type being discussed, regeneration of the gas is usually not practiced, but liquid fuel such as oil or tar is employed as a second fuel, the reason for the use of this liquid fuel being, in considerable measure, to furnish luminosity to the flame.

The advisability of gas regeneration varies with the gas, and, inversely, with the volume of air necessary to burn a unit volume of gas. Natural gas requires somewhat more than ten times its own volume of air for complete combustion; coke oven gas requires about five volumes; producer gas or blast furnace gas requires a much smaller ratio of air to gas, the requirement of blast furnace gas being somewhat less than the volume of the gas itself. It is well understood, therefore, that the relative advantage of regeneration of gas for the sake of increased temperature is a minimum with natural gas and a maximum with blast furnace gas.

An object of the present invention is to provide an improved construction for industrial furnaces or the like whereby the cracking of hydrocarbon gases for use in such furnaces may be accomplished efficiently.

A further object is to provide apparatus of the kind just referred to having means for cracking hydrocarbon gas by preliminary combustion of a portion of the gas to raise the temperature of the entire mass of fuel gas and products of combustion to a cracking temperature.

A further object is to provide improved apparatus of the kind referred to in which hydrocarbon gas may be used in mixture with blast furnace gas and in which the blast furnace gas may be regenerated, to the end that it will be introduced hot into the gas port of the furnace.

A further object is to provide a construction of the kind immediately above referred to in which gas ports of ordinary construction may be employed.

A further object is to provide an improved method of operating an industrial furnace whereby the desired luminosity of flame may be accomplished efficiently and at relatively low cost.

A further object is to provide a furnace construction and an improved method of furnace operation well adapted to meet the needs of commercial service.

Further objects will appear as the description proceeds.

Referring to the drawings—

Figure 1 is a top plan view, more or less diagrammatic in its nature, illustrating a portion of an industrial furnace embodying the principles of the present invention;

Figure 2 is a sectional view taken along the plane indicated by the arrows 2—2 of Figure 1;

Figure 3 is an end view taken in the direction of the arrow 3 of Figure 1;

Figure 4 is a view similar in many respects to Figure 2 but omitting the gas regenerator of Figure 2;

Figure 5 is a sectional view on an enlarged scale illustrating a gas port which may be used in the practice of the present invention;

Figure 6 is a view taken along the plane indicated by the arrows 6—6 of Figure 5; and

Figure 7 is a view similar to Figures 2 and 4 but showing another modification.

Referring first to Figures 1, 2 and 3, the numeral 11 indicates as a whole an open hearth furnace, this furnace having been chosen for purposes of illustration as being typical of a regenerative reversible furnace. The numeral 12 indicates a gas regenerator and the numeral 13 indicates an air regenerator cooperatively associated with the furnace 11 in the manner well understood by those skilled in the art. The numeral 14 indicates an uptake from the gas regenerator 12 communicating through the port 15 with the hearth of the furnace. The numeral 16 indicates a pair of uptakes from the air regenerator 13 leading to the air port 17, through which communication is had to the hearth of the furnace. A pipe 18 leads from the top of the air regenerator 13 to the cracking chamber 18a, preferably located on the outside of the furnace. Said cracking chamber 18a is located between the elbow 19 communicating with the pipe 18 and the elbow 20 communicating with the elbow 19 is the pipe 21 for conducting fuel gas, such as coke oven gas or other hydrocarbon gas, to the cracking chamber 18a. As so connected, said pipe 21 will increase the flow of air from the air regenerator 13 by aspiration.

The pipe 18 communicating from the air regenerator 13 is provided with the regulating valve 22, which is adapted to shut off completely communication between the cracking chamber 18a and the air regenerator 13. For the control of said valve 22, a thermocouple is provided, indicated by the numeral 23, which thermocouple communicates with the interior of the elbow 20. Said thermocouple 23 is connected to the controller 24, which in turn is connected to the operating cylinder 25 for operating said valve 22. In operation, the thermostat 23 will control temperatures at the entrance of the cracking chamber 18a at the minimum at which satisfactory cracking takes place, and the gases entering the port 15 by way of said cracking chamber 18a will be cracked by partial combustion in said cracking chamber to a sufficient extent to provide a luminous flame. At the same time, excessive combustion of the gas delivered through the pipe 21 is avoided. Though a thermostatic control for the valve 22 has been shown, it will be understood that any other control means may be used if preferred.

By reason of the construction referred to, a saving in original and maintenance costs is provided, together with good thermal performance due to regeneration of the blast furnace gas in the regenerator 12. It will be understood that wherever in this specification or in the claims the term "coke oven gas" is used, it will apply with equal correctness to natural gas or any gas containing hydrocarbons capable of being cracked through heat. The term "hydrocarbon gas" is intended to be generic to the gases referred to in this paragraph.

Figure 4 illustrates a construction in which the gas regenerator is omitted, a single fuel gas being employed, which gas contains hydrocarbons. Where such a fuel as natural gas or coke oven gas is to be used, it is not necessary or desirable to regenerate the gas, since regeneration of the air will pre-heat a very large proportion of the mixture of air and gas which unite in the furnace. As indicated above, however, it is extremely desirable to obtain luminosity in the flame. It is

also desirable to give a shape to the mixture of combustible gas issuing from the port and to determine its velocity.

In Figure 4 the furnace 11 includes the air regenerator 13. Said air regenerator 13 is connected through the pipe 26 to the cracking chamber 26a. The pipe 27 leads from the cracking chamber 26a to the gas port 15. The numeral 16 indicates a pair of air uptakes leading to the air port 17. Said air port 17 serves to conduct the products of combustion from the furnace to the regenerator 13 when the furnace is reversed. Gas containing hydrocarbons is conducted to the cracking chamber 26a through the pipe 21. If preferred, the gas containing hydrocarbons may be introduced through the pipe 21a into the pipe 26, whereby to produce aspiration of air by the gas issuing from the pipe 21a. The thermocouple 23 is connected in the pipe 27. Said thermocouple controls the regulator 24, which in turn controls the operating cylinder 25. Said operating cylinder 25 controls the position of the valve 28 located in the pipe 26 leading to the cracking chamber 26a. Said valve 28 is adapted to close completely communication between the cracking chamber 26 and the air regenerator 13. It will be understood, of course, that any other control means for the valve 28 may be utilized if preferred, instead of the thermostatic control illustrated.

The mode of operation of the structure shown in Figure 4 is to permit a regulated amount of air to rise in the cracking chamber 26a and to unite with the gas from the pipe 21 or the pipe 21a, the combustion within said cracking chamber raising the temperature of the gas to the cracking point. On reversal of the furnace, the valve 28 may be either open or closed, since there is but a single regenerator at each end of the furnace and the use of the pipe 26 and the cracking chamber 26a as a downtake is optional. However, important results are accomplished by closing the valve 28 when products of combustion are going into the regenerator 2. The volume of the fuel gas entering the furnace is small and the area of the port 15 may be very small and still afford sufficient area for passage of gas into the furnace. The volume of air in relation to that of gas is so large that there is an advantage in bringing the gas into closer communication with the air than is possible in a single port. If the valve 28 be held closed during reversal, there will be no passage of gases, solid matter, or slag vapors into the port 15. This fact permits a port construction in which multiple exits for the gas passing to the furnace are possible. Such a construction is illustrated in Figures 5 and 6, in which the gas port 15 has disposed therein the multitubular insert 29, by means of which it is possible to influence both speed of entry of gas into the furnace and the conformation of the surface along which mixture of air and gas takes place for combustion purposes.

Referring now to Figure 7, the air regenerator 12 has two uptakes 16 leading to the air port 17 similar to the construction shown in Figures 1 and 2, and has a central uptake 30 leading to the gas port 15. Gas containing hydrocarbons is introduced through the pipe 31 into the gas port 15.

In the construction illustrated in Figure 7, the air which has passed up through the central uptake 30 flows through the port 15 in a stream parallel to and surrounding the gas delivered by the pipe 31. By this means cracking will occur

as a result of combustion of the outer layer of the gas body. The port 30 is provided with the valve 32, which may be controlled by a cylinder 25 responsive to conditions at any preferred point, as for example in the port 15.

Though a preferred embodiment of the present invention has been described in detail, many modifications will occur to those skilled in the art. It is intended to cover all such modifications that fall within the scope of the appended claims.

What is claimed is—

1. The method of operating a reversing regenerative furnace fired with a fuel containing hydrocarbons which consists in admitting a regulated quantity of regenerated air into contact with said fuel prior to its introduction to the furnace, raising the temperature of the resulting mixture by partial combustion to crack part of the hydrocarbons contained in said fuel and thereafter introducing the resulting mixture to the furnace, admitting regenerated air to said furnace in contact with said gaseous mixture, and, when the furnace is reversed, stopping the flow of products of combustion along the path of said incoming gaseous mixture.

2. The method of operating a reversing regenerative furnace using a gaseous fuel which contains hydrocarbons and a gaseous fuel which does not contain hydrocarbons which consists in regenerating the fuel which does not contain hydrocarbons and admitting it to the furnace, admitting a regulated quantity of air to the gaseous fuel which contains hydrocarbons, bringing said last mentioned fuel to a cracking temperature and admitting it to contact with said gaseous fuel which does not contain hydrocarbons, and burning said two fuels in said furnace.

3. The method of operating a reversing regenerative furnace using a gaseous fuel which contains hydrocarbons and a gaseous fuel which does not contain hydrocarbons which consists in regenerating the fuel which does not contain hydrocarbons and admitting it to the furnace, admitting a regulated quantity of regenerated air to the gaseous fuel which contains hydrocarbons, bringing said last mentioned fuel to a cracking temperature and admitting it to contact with said gaseous fuel which does not contain hydrocarbons, burning said two fuels in said furnace, and, when said furnace is reversed, stopping the flow of products of combustion along the path of said regenerated air.

4. The method of operating a reversing regenerative furnace which consists in admitting independently regulated quantities of air in two paths, admitting hydrocarbon gas into contact with the air in one of said paths and cracking a portion of said gas by partial combustion thereof, allowing said paths to meet for combustion in the furnace, and on reversal of the furnace delivering products of combustion for regenerating purposes through only that path to which gas had not been admitted.

5. In combination, a reversing regenerative furnace having an air port and a gas port, an air regenerator connected to said air port for receiving products of combustion from said furnace when said furnace is reversed, a cracking chamber having an outlet for delivering gas to said gas port, means for delivering hydrocarbon gas to said cracking chamber, means connecting the outlet end of said air regenerator with said cracking chamber whereby regenerative air may be mixed with said hydrocarbon gas in said cracking chamber to partially crack said gas by

combustion in said cracking chamber, and means responsive to temperature conditions at said cracking chamber for automatically regulating the amount of regenerated air delivered from 5 said air regenerator to said cracking chamber.

6. In combination, a reversing regenerative furnace having an air port and a gas port, an air regenerator connected to said air port for receiving products of combustion from said furnace when said furnace is reversed, a cracking chamber having an outlet for delivering gas to said gas port, means for delivering hydrocarbon gas to said cracking chamber, means connecting the outlet end of said air regenerator with said cracking chamber whereby regenerative air may be mixed with said hydrocarbon gas in said cracking chamber to partially crack said gas by combustion in said cracking chamber, and means responsive to conditions at said cracking chamber for automatically regulating the amount of regenerated air delivered from said air regenerator to said cracking chamber.

7. In combination, a reversing regenerative furnace having an air port and a gas port, an air regenerator connected with said air port and a gas regenerator connected with said gas port, a cracking chamber, means for delivering hydrocarbon gas to said cracking chamber, means connecting said air regenerator with said cracking chamber whereby a supply of regenerated air may be mixed with hydrocarbon gas in said cracking chamber to crack a portion of the hydrocarbons in said gas, means for delivering the gas from said cracking chamber to said gas port, and means responsive to conditions in said cracking chamber for regulating the amount of air delivered from said air regenerator to said cracking chamber.

8. In combination, a reversing regenerative furnace having an air port and a gas port, an air regenerator connected with said air port and a gas regenerator connected with said gas port, a cracking chamber, means for delivering hydrocarbon gas to said cracking chamber, means connecting said air regenerator with said cracking chamber whereby a supply of regenerated air may be mixed with hydrocarbon gas in said cracking chamber to crack a portion of the hydrocarbons in said gas, means for delivering the gas from said cracking chamber to said gas port, and means responsive to conditions in said cracking chamber for regulating the amount of air delivered from said air regenerator to said cracking chamber, said last mentioned means being adapted to shut off communication from said furnace through said cracking chamber to said air regenerator when said furnace is reversed.

9. In combination, a reversing regenerative furnace having an air port and a gas port, an air regenerator connected to said air port, a

cracking chamber, means for admitting hydrocarbon gas to said cracking chamber, means for admitting air from the outlet end of said air regenerator to said cracking chamber whereby a portion of the hydrocarbons in said gas may be cracked, means for delivering gas from said cracking chamber to said gas port, and a valve adapted to shut off communication between said cracking chamber and said air regenerator, said gas port including a multiple-aperture means 10 for causing the flow of gas through said gas port in a plurality of streams.

10. In combination, a reversing regenerative furnace adapted to burn hydrocarbon gas and a gas which does not contain hydrocarbons, said furnace having a gas port, an air port, an air regenerator connected with said air port and a gas regenerator connected with said gas port, means for delivering hydrocarbon gas, a cracking chamber for receiving said hydrocarbon gas, 20 and means connecting said cracking chamber with said gas port, means connecting said air regenerator with said cracking chamber whereby regenerated air may be mixed with said hydrocarbon gas in said cracking chamber to crack 25 a portion of the hydrocarbons in said cracking chamber by partial combustion, and a shut-off valve in said connecting means between said air regenerator and said cracking chamber.

11. In combination, a reversing regenerative furnace having an air port and a gas port, an air regenerator connected to said air port, said air regenerator also having a connection with said gas port, means for delivering hydrocarbon gas to said gas port, and a shut-off valve for 35 closing communication between said gas port and said air regenerator upon reversal of said furnace.

12. In combination, a reversing regenerative furnace having an air port and a gas port, an air regenerator connected to said air port, said air regenerator also having a connection with said gas port, means for delivering hydrocarbon gas to said gas port, and a shut-off valve for closing communication between said gas port and 45 said air regenerator upon reversal of said furnace, said gas port having a multiple-aperture nozzle for causing gas to flow into said furnace in a plurality of streams.

13. In combination, a reversing regenerative furnace having an air port and a gas port, an air regenerator connected to said air port, said air regenerator also having a connection with said gas port, said gas port including a passage-way located within said furnace and adapted to 55 function as a cracking chamber, conduit means for delivering hydrocarbon gas to said gas port, and a shut off valve for closing communication between said gas port and said air regenerator upon reversal of said furnace.

ARTHUR J. BOYNTON.
